(57) CLAIM

The ornamental design for a rugged enclosure with a gaming system, as shown and described.

DESCRIPTION

FIG. 1 is a right side perspective view for rugged enclosure with a gaming system showing our new design;

FIG. 2 is a front perspective view thereof;

FIG. 3 is a top view with the lid closed thereof;

FIG. 4 is a right view with the lid closed thereof, the left view being a mirror image thereof;

FIG. 5 is a back view with the lid closed thereof;

FIG. 6 is a right view with the lid open thereof

FIG. 7 is a front view with the lid closed thereof;

FIG. 8 is a left view with the lid open thereof; and,

FIG. 9 is a front view with the lid open thereof.

The broken lines in FIGS. 1 and 2, depict environmental subject matter only and form no part of the claimed design.
